TRUSS FOR BICYCLE SADDLE SPRING ASSEMBLY

Bernard J. Bislich, Collierville, Tenn., assignor to Troxel Manufacturing Company, Moscow, Tenn., a corporation of Ohio

Filed Sept. 18, 1963, Ser. No. 76,633

Term of patent 14 years

(Cl. D90—16)

FIG. 1 is a side elevational view of a truss showing my new design.

FIG. 2 is a front elevational view thereof.

FIG. 3 is a bottom view thereof.

FIG. 4 is a back elevational view thereof.

The portions shown in broken lines are included for illustrative purposes only.

I claim:

The ornamental design for a truss for bicycle saddle spring assembly, as shown and described.
